UNITED STATES PATENT OFFICE.

MARY B. LOCKHART, OF PORTSMOUTH, VIRGINIA.

DESIGN FOR A CHEST OR SIMILAR ARTICLE.

57,981.

Specification for Design.

Patented May 24, 1921.

Application filed October 4, 1920. Serial No. 414,680. Term of patent 14 years.

To all whom it may concern:

Be it known that I, MARY B. LOCKHART, a citizen of the United States, residing at Portsmouth, in the county of Norfolk and State of Virginia, have invented a new, original, and ornamental Design for Chests or Similar Articles, of which the following is a specification, reference being had to the accompanying drawing, forming part thereof.

The figure is a perspective view of a chest showing my new design.

I claim:

The ornamental design for a chest or similar article, as shown.

MARY B. LOCKHART.
